Primary Examiner — Robert A Delehanty

(74) Attorney, Agent, or Firm — Calfee, Halter & Griswold LLP

(57) **CLAIM**

The ornamental design for a bath grip, as shown and described.

DESCRIPTION

FIG. 1 is a perspective view of a bath grip of the new design; FIG. 2 is a front elevational view of the bath grip of FIG. 1; FIG. 3 is a rear elevational view of the bath grip of FIG. 1; FIG. 4 is a left side elevational view of the bath grip of FIG. 1, the right side elevational view being a mirror image thereof; and, FIG. 5 is a top plan view of the bath grip of FIG. 1, the bottom plan view being a mirror image thereof. The portions of the Figures shown in broken lines are not part of the claimed design and are for illustration only.
